Primary Examiner — Susan Bennett Hattan*Assistant Examiner* — Jennifer Wright(74) *Attorney, Agent, or Firm* — Staas & Halsey LLP(57) **CLAIM**

The ornamental design for a lens for light emitting diode, as shown.

DESCRIPTION

FIG. 1 is a front view of the lens for light emitting diode showing the new design;

FIG. 2 is a rear view of FIG. 1;

FIG. 3 is a right side view of FIG. 1, the left side view being a mirror image thereof;

FIG. 4 is a bottom view of FIG. 1;

FIG. 5 is a top view of FIG. 1;

FIG. 6 is a cross sectional view in the direction of line 6-6 of FIG. 2.

FIG. 7 is a front, top and left side perspective view of FIG. 1; and,

FIG. 8 is a rear, top and right side perspective view of FIG. 1.

1 Claim, 8 Drawing Sheets(56)
